[57] CLAIM

The ornamental design for a three dimensional greeting card or similar article, as shown and described.

DESCRIPTION

FIG. 1 is a front perspective view of the three dimensional greeting card with a contained tape extended, showing my new design;

FIG. 2 is a front perspective view thereof with the tape retracted;

FIG. 3 is a front elevational view of a three-dimensional greeting card or similar article showing my new design reduced scale;

FIG. 4 is a rear elevational view thereof;

FIG. 5 is a top plan view thereof;

FIG. 6 is a side elevational view thereof, the undisclosed side being substantially the same;

FIG. 7 is a bottom plan view thereof; and

FIG. 8 is a bottom plan view of a second embodiment of FIG. 1, it being understood that the undisclosed top and sides are the same as in FIGS. 1-6.

Fig.3**Fig.4****Fig.5****Fig.6****Fig.7****Fig.8**
